Primary Examiner — T Chase Nelson*Assistant Examiner* — Jonathan J. Han(74) *Attorney, Agent, or Firm* — Abelman, Frayne & Schwab(57) **CLAIM**

The ornamental design for a charging handle, as shown and described.

DESCRIPTION

FIG. 1 is a front, right side, and bottom perspective view of a charging handle showing the new design;

FIG. 2 is a front elevation thereof;

FIG. 3 is a rear elevation thereof;

FIG. 4 is a left side elevation thereof;

FIG. 5 is a right side elevation thereof;

FIG. 6 is a top plan thereof; and,

FIG. 7 is a bottom plan thereof.

The broken lines are used for the purpose of illustrating unclaimed portions of the charging handle and form no part of the claimed design.

1 Claim, 6 Drawing Sheets(56)
